UNITED STATES PATENT OFFICE.

RICHARD N. WATROUS, OF ELMIRA, NEW YORK, ASSIGNOR TO HIMSELF AND
W. W. KELLOGG, OF SAME PLACE.

IMPROVEMENT IN THE CONSTRUCTION OF DIES FOR FORMING THE LIPS OF AUGER-BITS.

Specification forming part of Letters Patent No. 117,838, dated August 8, 1871.

To all whom it may concern:

Be it known that I, RICHARD N. WATROUS, of Elmira, in the county of Chemung and State of New York, have invented a new and Improved Die for Forming the Lips and Heads of Augers; and I do hereby declare that the following is a full, clear, and exact description thereof, which will enable others skilled in the art to make and use the same, reference being had to the accompanying drawing forming part of this specification, in which—

Figure 1 represents an end view of my improved die for augers. Fig. 2 is a side view, partly in section, of the same.

Similar letters of reference indicate corresponding parts.

This invention has for its object so to improve the construction of dies for forming the lips and heads of augers that the same can easily be repaired in case the projecting pin breaks off, and that the different requisites of hardness can be imparted to the several parts. The invention consists in the application of a removable pintle to the die, whereby the stated objects can be fully attained.

A in the drawing represents a block of steel suitable for the die required. It is so shaped at the striking-surface as to constitute the die for forming the lip and head of an auger. Into the striking-face of the die is bored a hole, preferably of slightly-conical form, into which is in-

serted a steel pintle, B, of tapering form. At the end of the pintle B is formed the pin or projection a, which gives form to the inside of the lip or cut of the auger. A hole, b, is bored into the opposite end of the die to permit the removal of the pintle B, by the insertion of a rod through b.

The advantages of this arrangement are manifold. The die and pintle can be tempered separately. The die, having to withstand the blow or pressure, must be very hard in order to be durable, while the pintle must have a spring-temper to prevent breaking.

Should the projecting pin a break, which it is liable to do, a new pintle can be inserted without great cost, while heretofore the entire die would have to be made anew. Both dies A C of a pair are or may be provided with such removable pintles, as shown.

Having thus described my invention, I claim as new and desire to secure by Letters Patent—

As an improvement in dies for swaging and forming auger-bits, the projection d on pintle B, made separate from the other parts of the die and inserted in the die-block in the tapering socket, and made removable therefrom in virtue of the holes b, as and for the purpose specified.

RICHARD N. WATROUS.
